PORTABLE FIELD OXYGEN THERAPY
APPARATUSWalter M. Boothby and William Randolph
Lovelace, II, Rochester, Minn.

Application March 23, 1942, Serial No. 435,916

10 Claims. (Cl. 128—191)

Our application relates to portable field oxygen therapy apparatus and has for its object to provide a suitable apparatus for permitting economic therapeutic use of oxygen in high concentrations with a closed circuit carbon dioxide absorption means, which shall be light in weight, easily portable, mounted within a carrying case of compact and effective design, and adapted to be used with all sizes of standard medical oxygen cylinders.

As the art of oxygen therapy has advanced under modern developments, certain conditions are known where it is desirable or essential to supply to individuals a certain gas or mixtures of gases for breathing, particularly oxygen with or without added air. These conditions are, of course, all essentially medical. The types of cases where oxygen supply is essential to preserve life, other than diseases of common knowledge such as pneumonia and the like, may be from injuries suffered, wherein shock, loss of blood and other conditions have reduced the patient's resistance to a low point, and quick administration of a high concentration of oxygen, in practice 100 percent oxygen, may make the difference between death on the part of the patient or his survival.

Such conditions are, of course, always present in and back of lines of military combat. Under such conditions, where large numbers of wounded or gassed individuals are to be found, it is of the utmost importance in many cases to be able to have quickly at hand, before hospitalization is possible, a means of supplying to the patient the requisite high concentration of oxygen. Under such conditions also, because of the difficulty of having comparatively heavy tanks of oxygen available in large numbers, it is important that supplies of oxygen available are conserved to as great a degree as possible so that such supplies as are available may be used with the fullest effectiveness.

It is a primary object of our invention therefore, to provide, in a compact easily portable arrangement, means for delivering oxygen to a patient, which can be taken from point to point on the field to be used on injured persons, particularly those wounded by military action, and whereby not only high concentrations of oxygen or 100 percent oxygen can be administered to the patient, but a closed breathing circuit is provided with means for removing carbon dioxide in said circuit so that the oxygen supplied may be repeatedly breathed and rebreathed.

It is, therefore, a further and highly important object of our invention to provide, in connection with a portable unit including means to quickly

set it up in working condition in the field, a closed breathing circuit, means for removing carbon dioxide from exhalation gases moving therethrough, means for supplying oxygen to the inhale side to be added to the substantially pure oxygen accumulated in a reservoir rebreathing bag after the carbon dioxide has been removed, and further to automatically increase the supply of oxygen for inhalation during the latter part 5 of the period of inhalation, all so mounted and regulated as to administer to the patient in the field a full supply of 100 percent oxygen necessary to meet the breathing needs of the patient while at the same time limiting the use of oxygen in all uses of the apparatus so as to conserve the main oxygen supply.

In this connection it is an object of our invention to provide a compact case generally cube-like in form, wherein the apparatus to be employed is permanently attached to and supported by a base portion of the case and wherein the main bulk of the case comprises a removable cover portion which when removed is adapted, first, to expose the operative elements supported by the 10 base portion, and second, to be employed as a table support to hold the parts supported by the base portion in position for use.

It is a further object of our invention to construct relatively the base portion and the cover portion of the case so that the latter can be withdrawn, arranged as a table support and have the base portion and parts carried thereby secured to it as a table support with the utmost quickness and at the same time so that the parts will be firmly and continuously held together in such new position, where they will be conveniently arranged for effective use.

It is a further object of our invention to provide supported from the aforesaid base portion of 40 the casing, a container for some granular or broken material adapted to absorb carbon dioxide, such as soda lime, which shall be supported transversely of the casing in such manner that the gases of exhalation will be caused to pass through the chamber and the carbon dioxide absorbing material therein, which shall be capable of being removed and yet with means for holding it gas-tight in the breathing line.

It is a further object of our invention to provide, in conjunction with the aforesaid base portion of the case, a pair of uprights rigidly held to said base portion and constituting means for supporting the instrumentalities above referred to, so 45 that when the deep cover portion of the case

is removed said instrumentalities will be conveniently accessible.

It is a further object of our invention to provide secured to the upright supports of the case, control mechanism for controlling continuous flow of oxygen gas in suitably regulated amounts to enter the breathing line at low pressure for the purpose of maintaining the requisite quantity of oxygen to make up for the loss thereof taken out or absorbed as carbon dioxide.

It is a further object of our invention not only to provide means for continuous flow of oxygen entering the closed breathing circuit, but to provide also valve mechanism subject to the negative pressure induced by inhalation which shall automatically increase the flow of oxygen into the breathing line after inhalation has proceeded to a point where the rebreathing bag is exhausted.

It is a further object of our invention to provide a rebreathing bag and connector tube thereto which may be carried within the case in a separated condition, in conjunction with means in the case co-operating with means on the rebreathing bag connector whereby the rebreathing bag may be quickly connected in the breathing line in position to be suspended outside the case.

It is a further object of our invention to provide means which may be carried in the case but normally separated from the other appliances for quick connection with any tank of oxygen which may be available, such as small tanks which may be carried from point to point by hand, or large tanks which would require movement from point to point upon some kind of trucking device.

It is a further object of our invention to provide breathing tubes which are connected together and have a single tube going to the mask, and which have branch tubes one for exhalation and the other for inhalation, which together, taken in conjunction with fixed passages in the machine, form the closed breathing circuit, said respective exhaling and inhaling tubes being respectively associated with flap valve constructions operating so that exhalation and inhalation cause flow of gases through the circuit always in one direction.

The full objects and advantages of our invention will more fully appear in the specification hereinafter presented, and the novel features by means of which the above noted advantageous results are secured will be particularly pointed out in the claims.

In the drawings illustrating an application of our invention in one form:

Figure 1 is a perspective view of the casing including the field apparatus.

Figure 2 is a plan view with some parts in section of the base portion of the apparatus, showing the general arrangement of parts carried thereby.

Figure 3 is a sectional view taken on the line 3—3 of Figure 2.

Figure 4 is a sectional view taken on the line 4—4 of Figure 2.

Figure 5 is a side elevation view of the entire apparatus set up for operation, indicating oxygen tanks of different sizes conveniently positioned for use.

Figure 6 is a side elevation view taken from the opposite side of the showing of Figure 5, illustrating the tube connections to the rebreathing bag and the mask.

Figure 7 is a detail showing a form of corrugated rubber which may be used for the extended

tube connections in the apparatus and going to the mask.

Figure 8 is a sectional elevational view when the apparatus is assembled for operative position, taken substantially along the line 8—8 of Figure 2.

Figure 9 is an enlarged sectional view taken through the valve control mechanism.

Figure 10 is a part sectional view of the valve mechanism for making connection with the filled oxygen tanks.

Fig. 11 is a diagrammatic view related to the structural showing of the other figures of the drawings and with appropriate legends applied, showing the travel of the gases in their continuous course from the beginning of the exhalation at the mask to the end of inhalation at the mask.

As illustrated, referring to Figure 1, the casing comprises a base portion 15 and a cover portion 16 held together by hasps 17, 18, 19, and 20, pivotally mounted upon and connected to the deep cover portion 16 in pairs on opposite sides thereof, as indicated in Figures 1, 5 and 6. These hasps are adapted to snap over catch portions 21, 22, 23 and 24 (see Figure 2), which are fast on opposite sides adjacent upper edges of the base member 15. This base member is also provided with similar catches 25, 26, 27 and 28, which are fast on opposite sides of the base member 15 adjacent the bottom edge thereof as clearly shown in Figures 1 and 5.

From a comparison of these figures, it will be apparent that when the casing is put together for ready transport the hasps 17, 18, 19 and 20 snap over the catches 21, 22, 23 and 24 and secure the deep cover member 16 to the base member 15 so that the parts carried by the base member 15 are held within the deep cover member. When in this position, a handle 29 secured to the top wall 30 of the cover member 15 provides a means of carrying the entire assemblage as simply and as conveniently as an ordinary suitcase may be carried.

When, however, it is desired to put the machine in condition for operation, the hasps 17, 18, 19 and 20 are taken away from the catches 21, 22, 23 and 24, and the cover portion is lifted off, exposing the parts theretofore within and protected by said cover portion which are supported by the base member 15. A series of short legs 31, 32, 33 and 34 projecting upwardly from the corners of the top 30 of the deep cover member 16, then form a ground contact support for said deep cover member 16 when it is inverted. In this inverted position, as shown in Figures 5, 6 and 8, the cover member 16 will form a table support for the base member 15 and parts carried thereby. By means of the handle 14 the base member 15 is lifted up and set on the top edge of the cover member 16 and the hasps 17, 18, 19 and 20 are swung upwardly over the catches 25, 26, 27 and 28. The base member thus is held upon the cover member, with all the parts carried by the base member exposed for operative use, and with the base member substantially integral with the cover member, which thus becomes a supporting table for the base member.

Within the side walls 35 and 36 of the base member 16 and secured to said side walls by rivets, bolts, glue, or other suitable securing means, are pieces 37 and 38 which as shown in Figures 2 and 8, extend across the full extent inside the casing base member 15 to engage with their ends the other opposite side walls 39 and 40, thus becoming in effect integral with the side

walls 35 and 36. The central portions of the pieces 37 and 38 are provided with upright standards 41 and 42, clearly shown in elevation in Figures 5 and 6, and shown in sectional plan in Figure 2. To these uprights the gas administering apparatus is secured so that all essential and operative parts thereof when the base member is positioned upon the cover member as shown in Figures 5 and 6, are exposed and available subject to the control of the operator.

As best shown in Figure 5 a supporting bracket 43 is secured at 44 and 45 to the uprights 41 and 42. This bracket 43 has a depressed portion as shown which receives and supports a cylindrical canister 46 of a cross sectional shape narrower than its diameter as clearly indicated in Figures 2 and 8. The canister 46 is held between a pair of spaced parallel cross bars 47 and 48, Figure 2, which are respectively formed with angle portions 49, 50, 51 and 52 bolted to the uprights 41 and 42. As shown in Figure 8, the side walls 53 and 54 of the canister 46 have at their central parts circular openings 55 and 56. An inlet tube 57, Figure 8, passes through an opening in the top of bar 47, being held to said bar by a grooved washer 58. Similarly an outlet tube 59 passes through an opening in the top of bar 48 and is held thereto by a grooved washer 60. The tube 57 has fast thereon a ring or washer 61. Between the washer 61 and the side wall 53 of canister 46, is an annular rubber gasket 62, and between the inner part of grooved washer 59 and wall 54 of canister 46 is an annular rubber gasket 63.

An annular piece 64 is provided with a central threaded opening 65, Figure 2, in which is threaded a knurled thumb screw 66. The piece 64 is carried upon arms 67 and 68 which have their ends pivoted in blocks 69 and 70 secured to the cross bar 47. In this manner the thumb screw 66 may be swung up or down to bring its point away from or into engagement with a seat 71, Figure 8, on the outside of the wall 72 forming a continuation of inlet tube 57 into a portion 73 thereof extending at right angles to tube 57.

From the above construction it will be apparent that the canister 46 is removably mounted in the apparatus and yet is held gas-tight when in operative position since, by screwing up on the knurled thumb screw, pressure can be simultaneously put on the rubber gaskets 61 and 63, whereby the openings into the canister through which extend the tubes 57 and 59 will be firmly sealed. When, however, it is desired to remove the canister the knurled thumb screw 66 may be screwed in the opposite direction, the holder made up of arms 67 and 68 may be dropped down and the respective tubes 57 and 59 be withdrawn from the openings 55 and 56 and the canister lifted out. A cap 74 is adapted to open and close the canister.

The tube 73 connects by means of a flexible tube 75 of corrugated rubber, as shown in Figure 7, with a connector member 76, Figure 3, which in turn is united with a valve casing 77 having therein a valve chamber 78 normally opening past a flap valve 79 to a chamber 80. The above parts are secured to the cross bar 48. The chamber 80 is provided with a standard spring outlet valve 81, Figure 3, which permits escape of exhalation gases when pressure builds up after the rebreathing bag has been completely filled.

The chamber 80 also is provided with a nipple 82 which connects by means of a flexible tubing 83, Figure 6, with one branch 84 of a Y-piece 85 from which extends a tube 86 going to the mask 75

structure 87. This constitutes the exhalation part of the breathing line going from the mask 87 through tube 86, Y-tube branch 84, tube 83, piece 81, tube 85, and tubes 73 and 57, to the interior of the canister 46 enclosing a body of material for absorbing carbon dioxide. It will be noted that the end of tube 57 extends into a chamber formed by a body of mesh or reticulate material 88 held away from the wall 53 of canister 46 so that the exhalation gases are caused to spread and travel in all directions through the carbon dioxide absorbent within the canister 46. Similarly the gases of exhalation after passing through the canister 46 and the carbon dioxide absorbing material therein, pass through a mesh 89 held away from the opening into the tube 59 and thence go into a Y-tube connector 90. From the Y-tube connector 90 the gas passes through one branch 91 thereof and a flexible tube 92 to a nipple 93 formed on a casting piece 94. The nipple 93 discharges into a chamber 95 within casting piece 94, Figure 4. A nipple 96 is provided with a threaded annular ring 97. A rigid tube 98 has fast thereon and sealed against its outer wall a rubber sleeve 99 which has an annular head 100 adapted to engage an annular seat 101 on the threaded annular ring 97. A knurled annular screw cap 102 has a threaded portion 103 which in conjunction with the threads on the ring 97 enables the tube 98 readily to be connected in gas-tight relation with the nipple extension 96. The tube 98 as shown in Figure 6, carries a depending portion 104 to which is attached a rebreathing bag 105. With this arrangement the rebreathing bag may quickly be attached to and detached from the assemblage so that the rebreathing bag may depend outside of the casing as clearly shown in Figures 2 and 6.

At the top of chamber 95 is an upwardly opening flap valve 106 which opens into a chamber 107 formed by an extension 108 of the casting piece 94, said extension being secured to the cross bar 48 as shown in Figures 2 and 4. The gases of exhalation will therefore pass through the passages above described, including the carbon dioxide absorbent material in the canister 46 and to the rebreathing bag 105 until it is fully filled. Then if there is further exhalation the pressure will build up in the exhale valve 81 to permit the last part of the exhalation—the part most heavily charged with carbon dioxide—to pass to atmosphere.

Oxygen is supplied to the apparatus from suitable oxygen tanks. These tanks may be of different sizes such as small tank 108 or large tank 109 as shown in Figure 5. In either case customary valve controls are employed including a reducing valve 110 and a gauge 111 for indicating the pressure at which gas is being delivered.

Connected with outlet passage from the tank 108 or 109 a block 112 is provided having a depending nipple 113 with a pin 114 at its outer end. A tube 115 is provided which is carried loose in the base preferably together with the reducing valve 110 and gauge 111 carried loose in the case. The tube 115 may be of any desired length. This tube has at each end thereof, Figure 5, slip-joint connector pieces 116 and 117, respectively. These connector pieces embody a rotary member including a bayonet slot 118. This bayonet slot takes over the pin 114 and by turning the member 116 or 117, the tube 115 at one end is connected to the nipple passageway 113 and at the other end to a corresponding nipple 119. The nipple passageway 119 is an

extension from valve casing 120. From the nipple passage 119 the oxygen passes to a chamber 121 in valve casing 120, and from there goes past a controlling needle valve 121a to a chamber 122. The needle valve is operated by a knurled hand nut 123. From chamber 122 the gas goes through a passageway 124 to a flow valve 125, the rate of flow being indicated on a scale 126. From the flow valve the gas goes through tubing 127 through an opening 128 into chamber 95. Oxygen is thus caused to flow continuously from the tank 108 or 109 into chamber 95, the rate of flow being determined by the flow gauge 126 as indicated on the scale 125 and controlled by the hand nut 123. This oxygen thus joins the gases of exhalation going to the rebreathing bag and is carried back on inhalation to the lungs of the patient.

From the valve casing 120 extends a tube 129, Figures 5 and 8, which leads to a valve casing 130, Figures 8 and 9. In a valve chamber 131 within casing 130 a valve disc 132 is pressed against a valve seat 133 by means of a spring 134. A pin 135 passes through a tubular guide 136. One end of the pin 135 engages the center of the valve disc 132 and the other end of the pin engages a contact ball 137 on the end of a lever 138 eccentrically mounted with reference to the contact ball 137 at 139. The lever 138 in turn has a finger 140 which engages a contact ball 141 on a lever 142 pivoted at 143 to a casing 144. The levers 138 and 142 are within a chamber 145 inside of casing 144. A diaphragm 146 is sealed at its edges as indicated at 147 into the walls of casing 144 which, as indicated in Figure 8, is substantially circular in its back plan portion. Connected with the end 148 of lever 142 is a plate 149 which engages the central body portion of the diaphragm 146. The casing 144 is secured to the upright 42 by means of a collar 150, as shown in Figure 9. The opening through this collar exposes the diaphragm 146 to atmospheric pressure and other openings 151 and 152 further expose the diaphragm to atmospheric pressure. It follows that when the pressure within chamber 145 is reduced, air pressure will move the diaphragm inwardly into said chamber, correspondingly moving levers 142 and 138 so that the contact ball 137 engaging the pin 135 will cause the valve disc 132 to be pushed away from valve seat 133, and permit oxygen to flow into and through chamber 145 and a passageway 153 leading therefrom to the inhale side of the closed breathing circuit as will now be described.

To branch 154 of Y-connector in the breathing line is secured the inhalation tube 155, Figure 6, which connects with a nipple 156, Figure 4, formed on the casing extension 108 and opening into the chamber 107 above flap valve 106. From this arrangement it follows that when inhalation takes place the flap valve 106 will be lifted, the gas from rebreathing bag 105 will pass through the tube 98, chamber 95, past flap valve 106 into chamber 107, and from said chamber through extension passageway 156 and tube 155 to the common passageway 86 and mask 87. Along with the gases from the rebreathing bag will go the normal oxygen supply from tube 127 opening into chamber 95 at 128. When the rebreathing bag 105 has been exhausted and is collapsed, the pressure will be lowered through tube 91 and the canister 56 will be emptied of its gas. This lowering of pressure will in turn lower the pressure in branch 157, which branch is connected by tube 158 with the nipple extension 153. The

reduction of pressure will therefore be communicated to chamber 145 with the result that the diaphragm will cause the lever system to open the oxygen valve and an increase of oxygen will be delivered to the patient.

In chamber 107, Figure 4, is located an inhalation valve construction 159. When the pressure within chamber 107 and the valve member 159 reduces sufficiently, the spring held valve disc 160 will be moved to open to atmosphere through a passageway 161 which communicates past a whistle reed 162 with an opening 163 to atmosphere. This will enable air to be mixed with the mixture of rebreathed gases and oxygen going to the patient and when this occurs the movement of the reed will cause a whistling or musical sound which will notify the operator that air is being admitted.

As shown in Fig. 11, to which this outline of the course of the gas applies, with supporting references to other figures of the drawings, the course of the gas may be traced as follows:

From the mask 87 through a tube 86 exhalation gases pass through a branch 84 of Y tube 85, through a conduit 83 to and through a valve casing 71 and past check valves 79 therein, Fig. 3, and thence through tube 75 and connector member 73 and through tube 57 past connector member 61, by means of which soda lime container 46 is removably united by coupling means 61 in the exhale side of the breathing line, Figs. 5 and 8, to and through the soda lime container 46. A corresponding connector member 60 associated with tube 59, Fig. 8, removably connects the soda lime container at its other side with a Y tube 90, Fig. 6.

To one of the branches 91 of said Y tube, a tube 92 makes connection with a nipple 93 extending from a casing 94, Figs. 4 and 6. A lower chamber 95 therein below check valve 106 connects through a branch pipe 98, Figs. 2, 6, and 8, with a rebreathing bag 105 which is removably supported upon arm 98. Chamber 95 is also connected with oxygen supply tube 127. Above valve 106 in casing 94 is a second chamber 107, Fig. 4, from which leads a connector member 156, Figs. 2 and 4. From connector member 156 inhalation tube 155 leads back to Y tube 154 and closes the circuit.

50 The exhaling side of the closed circuit thus comprises passages and chambers including common tube 86 from mask 87, connector tubes 83 and 73, the soda lime container 46, and connector tubes 90, 91, 92 to the reservoir rebreathing bag. 55 Exhalation pressure upon the valve 106 will maintain the exhalation side closed at that point. The inhalation side of the closed circuit likewise has connection through common mask conduit 86, Y tube 154, inhalation tube 155, connector 156, 60 valve chamber 94, past valve 106 to the reservoir rebreathing bag 105. The inhalation side also may to a limited extent withdraw gas from soda lime container 46, but the negative pressure in tube 83 will hold check valve 79 closed and substantially effect closure of the inhalation side at the reservoir rebreathing bag.

Oxygen supply means is also indicated in the diaphragm. From the oxygen tank 109 oxygen is delivered past known valve and pressure reducing mechanism to the delivery tube 115, 119, Fig. 5. From the tube 119, Fig. 10, the gas goes into a needle valve casing 120 controlled by a customary needle valve operated by valve handle 123, Fig. 10. From there, in such amounts as the operator may determine, oxygen will be delivered

from nipple 124, through a tube 125 of a flow valve, such as that disclosed in Heidbrink Patent 2,073,372, and by tube 137 into rebreathing chamber 95, Figs. 4 and 8. The volume of oxygen being delivered is indicated by the flow valve gauge 126. When oxygen is so furnished, its delivery will be continuous and in effect to the inhalation side of the breathing circuit. Continuous delivery of oxygen is not, however, always essential.

From the valve casing 120 and below the needle valve therein, a conduit 129, Figs. 8, 9, and 10, leads to a valve chamber in a casing 144 wherein, as shown in Fig. 9, through action of the diaphragm 146 when pressure is reduced by inhalation and emptying of the reservoir rebreathing bag, the valve operating mechanism will release oxygen to flow through tube 153, Y-tube 157, Y-block 90, and back through tubes 91 and 92 into the inhalation breathing line.

The advantages of our invention have appeared to a very considerable degree in the foregoing description. Not only is the apparatus admirably adapted for quick transport to points where emergency use is called for, but it provides special facilities for the admission of oxygen in any desired concentration without undue waste of the expensive oxygen gas. Under normal conditions the breathing circuit will be maintained continuously closed there being just enough admitted by means of controlled delivery through pipe 127 to compensate for the loss of oxygen absorbed in the alveolar regions of the lungs and withdrawn by the carbon dioxide absorbent material in the absorber canister. By the means described, the apparatus may be completely filled with 100% concentration of oxygen before the mask is applied and breathing starts, so that from then on the patient will be breathing substantially pure oxygen, loss through fixation of the oxygen of carbon dioxide being made up by the constant delivery from the regulated and controlled source through the flow valve and the tube 127.

When, however, breathing difficulties are encountered so that there is need of additional supply of oxygen over that furnished by the flow valve control, the automatic arrangement will supply the needed added oxygen. It is true also that all gases of exhalation going to the rebreathing gag must in the course of their passage through the machine, go through the canister containing carbon dioxide absorbing material, such as soda lime or the like, and have removed therefrom the carbon dioxide coming from the patient's lungs.

There is thus provided a complex and efficient closed circuit gas administering mechanism which may be transported as easily and as conveniently as an ordinary suitcase, which in its inoperative condition is entirely protected and closed, and yet which may be put into operative position with the parts thereof fully exposed and available for use with very little effort and substantially no consumption of time, and in the field away from hospital or other fixed medical facilities.

We claim:

1. A portable field oxygen therapy apparatus, comprising a casing having a base portion and a cover portion, said portions being removably connected together, means for controlling the administration of oxygen secured to the base portion and held within the cover portion when the cover portion is in normal closing position, means whereby the cover portion may be removed from the base portion to form a support for the base

portion, and means for securing the base portion to the cover portion for completing the operative unit with the gas controlling means exposed.

2. A portable field oxygen therapy apparatus, 5 comprising a casing having a base portion and a cover portion, means for controlling the administration of oxygen secured to the base portion and held within the cover portion when the cover portion is in normal closing position, means adapted to hold the said portions in such normal closing position so that they may be carried together but which permits separation of the parts, said cover portion when the parts are so separated being adapted to form a support for the base portion, and means on the base portion adapting the cover portion to be secured to the base portion to form a support for said oxygen administering means including the same elements which normally hold the base and cover portions together.

3. A portable field oxygen therapy apparatus, comprising a base portion having secured thereto means for controlling the administration of oxygen held so as to be exposed above the upper limits of the base portion, a deep cover portion adapted normally to enclose said oxygen administering means and to be removably secured to the base portion, said cover portion when removed and inverted forming a support for the base portion and said oxygen administering means, and means for connecting the cover and base portions together in either of said relative positions.

4. A portable field oxygen therapy apparatus, comprising a base portion having secured thereto 35 means for controlling the administration of oxygen held so as to be exposed above the upper limits of the base portion, a deep cover portion adapted normally to enclose said oxygen administering means and to be removably secured to the base portion, said cover portion when removed and inverted forming a support for the base portion and said oxygen administering means, pivoted hasps on opposite sides adjacent the lower edge of the cover portion when in normal position and the upper edge of the cover when in inverted position, and correspondingly positioned catches adjacent the upper and lower edges respectively of opposite sides of the base portion for connecting the cover and base portions together in either of said relative positions.

5. A portable field oxygen therapy apparatus, comprising a box formed with a shallow base portion and a deep cover portion, frame members secured to opposite sides of the base portion and having uprights extending a distance outside of said walls so that said uprights and the parts carried thereby are adapted to be enclosed within the cover portion, means for controlling the administering of oxygen secured to said uprights so as to be exposed above the upper limits of the base portion, and means removably securing the cover member to the base portion.

6. A portable field oxygen therapy apparatus, 65 comprising a box formed with a shallow portion and a deep cover portion, frame members secured to opposite sides of the base portion and having uprights extending a distance outside of said walls so that said uprights and the parts carried thereby are adapted to be enclosed within the cover portion, means for controlling the administering of oxygen secured to said uprights so as to be exposed above the upper limits of the base portion, pivoted hasps on opposite sides adjacent the lower edges of the cover por-

tion when in normal position, and the upper edge of the cover when in inverted position, and correspondingly positioned catches adjacent the upper and lower edges respectively of opposite sides of the base portion for connecting the cover and base portions together in either of said relative positions.

7. A portable field oxygen therapy apparatus, comprising a casing having a shallow base portion and a deep cover portion, said portions being removably connected together, and being adapted to be united so that the cover portion will form a table support for the base portion, a container of material for absorbing carbon dioxide supported upon the base portion, a closed breathing circuit extending from a mask and comprising exhalation and inhalation tubes, said container being connected to said exhalation tube, a connection for a rebreathing bag communicating with both the exhalation and inhalation sides of the closed circuit, a rebreathing bag and means removably attaching it to said connection so the rebreathing bag will be suspended outside of the casing, and means controlling the flow of gases in the closed circuit whereby gases of exhalation move to the rebreathing bag and gases of inhalation move from the rebreathing bag, said gases moving through the container of carbon dioxide absorbent in the same direction.

8. A portable field oxygen therapy apparatus, comprising a casing having a shallow base portion and a deep cover portion, said portions being removably connected together, and being adapted to be united so that the cover portion will form a table support for the base portion, a container of material for absorbing carbon dioxide supported upon the base portion, a closed breathing circuit extending from a mask and comprising exhalation and inhalation tubes, said container being connected to said exhalation tube, a connection for a rebreathing bag communicating with both the exhalation and the inhalation sides of the closed circuit, a rebreathing bag and means removably attaching it to said connection so the rebreathing bag will be

suspended outside of the casing, means controlling the flow of gases in the closed circuit whereby gases of exhalation move to the rebreathing bag and gases of inhalation move from the rebreathing bag, said gases moving through the container of carbon dioxide absorbent in the same direction, and means for delivering a continuous stream of oxygen at a predetermined and controllable rate of flow to the rebreathing bag and the inhale side of the closed breathing circuit.

9. In a portable field oxygen therapy apparatus embodying chambers and passageways to provide a closed breathing circuit with a rebreathing bag connected to both the inhale and the exhale sides thereof and a soda lime container in the exhalation side for removing CO₂, a box comprising a portable housing for said instrumentalities to the base of which they are severally attached, a cover completing said housing and adapted in inverted position to support the base and said instrumentalities when out in the field in operative position, and flexible and extensible means mounted on said base for removably connecting the said instrumentalities with an oxygen tank.

10. In a portable field oxygen therapy apparatus embodying chambers and passageways to provide a closed breathing circuit with a rebreathing bag connected to both the inhale and the exhale sides thereof and a soda lime container in the exhalation side for removing CO₂, a box comprising a portable housing for said instrumentalities to the base of which they are severally attached, a cover completing said housing and adapted in inverted position to support the base and said instrumentalities when out in the field in operative position, flexible and extensible means mounted on said base for removably connecting the said instrumentalities with an oxygen tank, and means for removably connecting in the system outside the limits of the box a suitably large rebreathing bag.
